(57) **CLAIM**

The ornamental design for a vegetable spray, as shown and described.

DESCRIPTION

FIG. 1 is a front perspective view of the vegetable spray showing my new design;

FIG. 2 is a rear perspective view thereof;

FIG. 3 is a left side elevational view thereof;

FIG. 4 is a rear elevational view thereof;

FIG. 5 is a top plan view thereof;

FIG. 6 is a front elevational view thereof;

FIG. 7 is a bottom plan view thereof; and,

FIG. 8 is a right side elevational view thereof.

The broken line showing of part of the activation button in FIG. 7, and of the internal annular shoulders in FIG. 7, are for purposes of illustration only and form no part of the claimed design.
